UNITED STATES PATENT OFFICE.

ULRIKA LÖFGREN, OF LOWELL, MASSACHUSETTS.

DOLL.

1,255,446.

Specification of Letters Patent.

Patented Feb. 5, 1913.

Application filed October 7, 1913. Serial No. 793,946.

To all whom it may concern:

Be it known that I, ULRICA LÖFGREN, a citizen of the United States, residing at Lowell, in the county of Middlesex and State of Massachusetts, have invented certain new and useful Improvements in Dolls, of which the following is a specification.

This invention relates to dolls. Its principal purpose is to provide a doll suitable for young children which is so made that there are no hard parts such as tips, points or ends which protrude so as to cause injury to the child, and which at the same time is so stiffened and made that it has a distinct shape which it will retain. My doll thus differs from the so called rag doll or dolls which have no skeleton or stiffening.

It is so made that all parts are flexible or pliable and so that the limbs and head can be bent into many desired positions and that when so bent, they will maintain their bent positions.

While principally intended for the use of children, they are also of great value in window decorations as from their flexibility, pliability and adaptability they can be used in a great variety of ways. They are also useful for favors at dances, for table and Christmas tree decorations, etc.

By making the frame work of copper wire, my doll will not be injured by water as the wire will not rust. By using oil paints and either fixed dyes or bleached material for the covering and other parts, my doll may be even soaked in water or washed without injury thereto.

In the drawings, Figure 1 shows the skeleton or frame. Fig. 2 shows the second step in the process of manufacture wherein the filling for the head is bound in place. Fig. 3 shows the condition of the device at a little later stage in the process of manufacture wherein the head has been covered ready to be painted while the filling of the body is in place as well as the filling of both arms and both legs while one arm has its knitted covering also in place. Fig. 4 is a front view of the completed doll. Fig. 5 is a side view of the completed doll showing some positions into which the arms and legs can be bent. Fig. 6 shows another method of bending the wire between the arms, legs and head.

The skeleton or frame is preferably made of a single piece of wire A. This wire

should be preferably pliable and non-elastic so that it can be easily bent and will retain the shape to which it is bent. I prefer the ordinary insulated copper wire used for electric wiring as it has about the right pliability and the presence of the insulation not only helps to give the desired consistency but gives a better hold for the filling than bare metal wires would give, whereby it is better held in place.

Any pliable and non-elastic wire may be used and it may or may not be closely covered with some fabric to which the filling will tend to cling as in the case of insulated wire.

This wire is bent to form a loop or preferably a double loop 10 for the head and is then narrowed in at 11 for the neck after which in any desired way, it is bent to form the arms 12 and 13 and the legs 14 and 15 all of which are so made that the wire is double and terminates at the position of each hand and foot in a loop. The end or tip 16 of the wire is brought down inside and the other end or tip 17 is preferably wound around the four sections of leg wires and the end 16, the tip 18 being pinched in close to what might be called the back bone. The result of this construction is that there are no ends or tips of the wire in any exposed positions, as the tip of 16 is thoroughly covered up and the tip 18 is afterward covered by the filling for the body as will be explained hereafter. To hold the head, arms, and legs together, the wire may be bent as shown in Fig. 1, or in Fig. 6, or in any other suitable way.

Referring to Fig. 2, the next step is to take a wad or ball B of cotton or other suitable preferably compressible material of such a size that when compressed it will be the size of the head desired, and to shape this around the skeleton head 10. By means of yarn or thread 20 the ball B is bound around and under the junction between the arms and the back bone and around the skeleton neck 11.

I use for the outside covering of my doll, knit goods such as stockinet, eiderdown or other similar material which is flexible and preferably elastic.

Over the filling B, I stretch the covering C of knitted textile material which is suitably rounded, shaped and sewed preferably at the back into the shape of a head. This

2
may be finished at the top with a cap 21 as shown. I prefer to have the knitted material of the head cover C extend below the neck as shown at 22 and to tie material C in at the neck by yarn or thread 23 whereby the head is properly shaped and is also held firmly to the skeleton.

The filling D for the body may be of similar material to that of the head B and is shaped around the back bone and the tops 10 of the legs 14 and 15 and is preferably loosely tied in place by yarn or thread 30.

At this stage also, the arms are wound preferably with strip material such as sheet 15 wadding 40, 41, 42 and 43 which holds itself in place sufficiently without further fastening by thread or yarn.

The arms are preferably covered with knit material E and F, which is sewed to a size 20 to fit closely over the filling 40 or 41 and is then drawn into place and sewed to the head covering extension 22. The body and legs are preferably covered with a single piece 25 of knit material formed with a body G and legs H and K. It is so cut and sewed that the legs will fit smoothly over the filling 42 and 43 of the legs and the body over the body filling D. The top is then brought up around the neck and sewed to the shoulder 30 ends of the arm coverings E and F and to the head covering extension 22.

To cover the seams around the neck and for ornamentation, I prefer to sew on an ornamental ruffle L. When the parts are 35 all in place, the face can be painted on to face covering C and the body G and arms as well as cap 21 may be painted in any design desired. I prefer to use oil paints for this purpose of such a character that they 40 cannot be sucked off to the injury of the children and I prefer to make my dolls of white bleached undyed knitted goods so that there will be no dyes to injure the child.

In Fig. 5, I show various positions to 45 which the legs and arms can be bent in which positions they will remain until forced to a different position. The dolls so constructed may be made to support one another in the standing position, to hang by the hands from 50 above, to stand supported by a staff, to appear to be walking or dancing together and to assume various ornamental and unique postures.

It will be noted that the arms and legs 55 can be bent at any point and in any direction as they are thin and uniformly pliable and not merely at the elbows and knees. The head may be bent within certain limits and it is so firmly attached to the skeleton 60 and to the body that it is not injured or weakened by being so bent.

My device has a skeleton which is pliable and non-elastic, while the filling is flexible and preferably compressible and the skin or 65 cover is flexible and preferably elastic.

While my preferred construction has a complete skeleton with a backbone and with arms, legs and head all formed of a single wire so bent that each is double with a loop at the end, and all tips are brought in closely to the backbone and the wire is pliable and non-elastic, I do not confine myself to a wire which is pliable and non-elastic. When any wire is so made into a skeleton that the arms and legs each include a wire so doubled 70 that there is a loop at the end and the tips are brought inside the body, it is included in my invention.

I claim:

1. A doll comprising a pliable and non-elastic wire frame formed with arms and legs each made of wire so bent as to be double with a loop at the end with no tips in the arms or legs, combined with a filling for 80 the head and body, a cover for the head and body, and flexible covering for the arms and legs.

2. A doll comprising a pliable and non-elastic wire skeleton formed with a back bone and in which the arms, legs and head 90 are formed of wire so bent as to be double with a loop at the end and all tips are brought in closely to the back bone, combined with flexible filling, and a flexible covering for the filling as described. 95

3. A doll comprising a skeleton of one piece of flexible wire formed with a back bone and arms and legs so bent as to be double with a loop at the end and both tips brought in closely to the back bone, a flexible filling, and a knitted textile material covering for the filling as described.

4. A doll which comprises a skeleton formed of one piece of pliable and non-elastic copper wire with a back bone and so 1 bent that the arms and legs are double with a loop at the end and both tips are brought in closely to the back bone, a fabric which closely covers said wire, and a flexible filling, together with a covering for the filling of 1 knitted textile material as described.

5. A doll comprising a wire skeleton formed with arms and legs each made of wire so bent as to be double with a loop at the end and with all tips brought inside the body, combined with a body filling which covers said tips, and a flexible covering for the arms and legs.

6. A doll comprising a pliable and non-elastic wire skeleton formed with a back bone and in which the arms and legs are formed of wire so bent as to be double with a loop at the end and with all tips brought in closely to the back bone, combined with a body filling which covers said tips, and a flexible and elastic covering as described.

7. A doll comprising a pliable and non-elastic wire skeleton formed with arms and legs each made of wire so bent as to be double with a loop at the end and with all tips

brought inside the body, combined with a body filling which covers said tips, and a flexible and elastic covering as described.

8. A doll comprising a pliable and non-
5 elastic wire skeleton formed with arms and legs each made of wire so bent as to be double with a loop at the end and with all tips brought inside the body, combined with a body filling which covers said tips, and a
10 covering for the arms, legs and body of knitted textile material as described.

9. A doll which comprises a skeleton formed of one piece of closely covered copper wire with a back bone and so bent that each arm and leg is double with a loop at the end and both wire tips are brought in closely to the back bone, a filling for the body which covers said tips, and strip material which incloses the double wire of each arm and leg, together with a covering for the arms, legs and body of knitted textile material as described.

10. In a doll, a pliable wire skeleton formed with a back bone and with arms and legs formed of wire so bent as to be double with a loop at the end of each and with all tips brought in closely to the back bone.

11. A doll comprising a pliable wire skeleton formed with arms and legs each made of wire so bent as to be double, with a loop at the end and with all tips brought inside the body, combined with a body filling which covers said tips, strip material which in-

closes the double wire of each arm and leg, together with a covering for the arms, legs 35 and body of knitted textile material as described.

12. In a doll, a skeleton having arms and legs each formed of wire so bent as to be double with a loop at the end of each and 40 with all tips brought in closely to the back bone.

13. A doll comprising a pliable and non-elastic wire frame formed with arms and legs each made of wire so bent as to be 45 double with a loop at the end with no tips in the arms or legs, and a flexible covering for the arms and legs.

14. A doll comprising a pliable and non-elastic wire frame formed with arms and 50 legs each made of wire so bent as to be double with a loop at the end with no tips in the arms or legs.

15. A doll comprising a pliable and non-elastic wire frame formed with arms and 55 legs each made of wire so bent as to be double with a loop at the end with no tips in the arms or legs, combined with a head and body, all wire tips being covered and protected by the head or body. 60

In testimony whereof I hereto affix my signature in presence of two witnesses.

ULRIKA LÖFGREN.
